UNITED STATES PATENT OFFICE.

LANNES N. HANSELL, OF SANFORD, FLORIDA.

AUTOMATIC SWITCH LOCK FOR RAILWAY SWITCHES.

Application filed August 8, 1927. Serial No. 211,489.

This invention relates to improvements in automatic switch locks for railway switches. The primary object of the invention resides in a means by which the actuating lever of a railway switch may be automatically locked in set position where it is prevented from accidentally swinging to an opposite position during the passage of a fast moving train over the switch, the result of which 10 is frequently the cause of serious train wrecks.

Another object of the invention is to provide an automatic switch lock for preventing a switch from being left partly open or "cocked", thus assuring absolute safety, and 15 which switch cannot be operated by an unauthorized person as the same is key controlled, thus insuring the operation of the same by an authorized person having the necessary key.

20 A further object is the provision of an automatic switch lock which is simple in construction, inexpensive of manufacture and positive in operation.

With these and other objects in view, the 25 invention resides in certain novel construction and combination and arrangement of parts, the essential features of which are hereinafter fully described, are particularly pointed out in the appended claims, and are 30 illustrated in the accompanying drawing, in which:—

Figure 1 is a perspective view of a switch stand showing my invention thereon.

Figure 2 is an enlarged vertical sectional 35 view through the switch actuating lever and lock mechanism.

Figure 3 is a vertical sectional view on the line 3—3 of Figure 2.

Referring more particularly to the drawing, the reference numeral 10 designates a 40 railway switch stand which includes the usual base 11, vertical sliding and turnably mounted collar 12, and rotatable signal post or support 13. The switch actuating lever is shown at 14, one end of which is bifurcated 45 as at 15 to provide spaced arms 16, the ends of which are pivoted to the bottom of the signal post 13 as at 17. The outer free end of the lever is curved outwardly as at 18 and 50 serves as the manipulating portion, the extreme end of the same having a ball weight 19 thereon for normally holding the lever in a down position. Links 20 have one end pivoted to the lever adjacent the pivoted end 55 thereof, while the other ends are pivoted to

the collar 12 for operatively connecting the collar with the actuating lever. In switches of this kind, it is necessary to lift the lever to a horizontal position before it is possible to impart rotation to the collar which collar in turn actuates the switch mechanism. This construction is present in hand switches now used on railways so that a detail explanation of the construction is not believed necessary.

For locking the lever in a set position, that is, either with the switch open or closed, I provide an arcuate shaped lug or tongue 21 which extends horizontally from the collar 12 and which is cast therewith. The top edge of the tongue is provided with a series of ratchet 60 teeth 22 for co-acting engagement with a latch bolt now to be explained.

Mounted in the bifurcation 15 of the actuating lever 14 is a lock mechanism 23 disposed on a plane above the tongue 21 when the lever is in a down position. The lock mechanism comprises a casing or housing 24' fitted and fixedly supported between the arms 16, and in which a vertically slidable latch bolt 24 is mounted for extension through an opening 25 in the bottom of the lock casing. A spring 26 bears against the latch bolt to normally extend the same beyond the lock casing and in the path of the ratchet teeth 22, so as to automatically engage the ratchet teeth when the lever is in a down position.

Outward movement of the latch bolt is limited by a shoulder 26' provided thereon for engagement with the bottom of the lock casing. The outer side wall of the lock casing 80 is provided with a key hole slot 27 for the insertion of a key 28 which engages a ward 29 in the latch bolt to facilitate of the retraction of the latch bolt when it is desired to lift the lever to swing the collar 12 and signal post 13 to a set position. After the lever has been swung clear of the tongue 21, the key may be removed, and upon release of the lever, the weight 19 will automatically swing the lever to a down position for automatic locking engagement of the latch bolt with one of the ratchet teeth 22.

From the foregoing description, it will be seen that I have provided an automatic switch lock by which a railway switch may be locked in any given set position, thus assuring absolute safety in preventing the switch being left partly set or cocked. The invention dispenses with the usual practice of using a padlock for holding the lever in 95 100 105 110

a locked position and which through negligence, may not be replaced and properly locked.

While I have described what I deem to be the most desirable embodiment of my invention, it is obvious that many of the details may be varied without in any way departing from the spirit of my invention, and I therefore do not limit myself to the exact details 10 of construction herein set forth nor to anything less than the whole of my invention limited only by the appended claims.

What is claimed as new is:—

1. A railway switch lock comprising an 15 actuating lever and an actuatable part of a railway switch, a lug extending from said last named part having a series of ratchet teeth thereon, a lock mechanism mounted on said lever including a vertically positioned spring 20 pressed latch bolt disposed in the path of said ratchet teeth for engagement therewith, and

a weight on the outer end of said actuating lever whereby the lever will be moved by gravity into locking engagement with the ratchet teeth when released by an operator, 25 substantially as set forth.

2. A railway switch lock comprising a pivoted bifurcated actuating lever and a part actuated thereby, an arcuate lug extending from said last named part and having a series 30 of ratchet teeth thereon, a key controlled lock mechanism mounted within the bifurcation in the said actuating lever, said lock mechanism including a latch bolt movable by gravity assisted by a spring into the path of said 35 ratchet teeth for engagement therewith, and a weight on the outer end of said lever whereby the lever will normally hold the switch in locked position, substantially as set forth.

In testimony whereof I hereby affix my 40 signature.

LANNES N. HANSELL.
